UNITED STATES PATENT OFFICE.

LOUIS F. DIETER, OF BUFFALO, NEW YORK.

METHOD OF AND MEANS FOR ROLLING OR FORMING CAR-WHEELS OR OTHER CIRCULAR BODIES.

1,319,141.

Specification of Letters Patent. Patented Oct. 21, 1919.

Continuation of application Serial No. 633,343, filed June 15, 1911. This application filed June 22, 1917. Serial No. 176,333.

To all whom it may concern:

Be it known that I, LOUIS F. DIETER, a citizen of the United States, residing at Buffalo, in the county of Erie and State of New York, have invented a novel and useful Method of and Means for Rolling or Forming Car-Wheels or other Circular Bodies, of which the following is a specification accompanied by one sheet of drawings.

10 The features of my invention claimed herein are related to the invention of my original application for patent filed June 15, 1911, Serial No. 633,343, Patent No. 1,243,050. This application is a continuation of my 15 said original application, and, for carrying out my invention I prefer to use an apparatus or mill, such for instance as shown and described in my said original application, and the connecting-parts of such an apparatus or mill shown in the accompanying drawings are illustrative of parts of my 20 said original application.

The subject-matter of this invention is partly described in and certain features of the invention herein described, but not herein claimed, are claimed in my following applications, viz: said original application for patent filed June 15, 1911, Serial No. 633,343, Patent No. 1,243,050; application 25 for patent filed October 10, 1916, Serial No. 124,921, Patent No. 1,243,051; application for patent filed November 20, 1916, Serial No. 132,372, Patent No. 1,243,052; application 30 for patent filed November 22, 1916, Serial No. 132,815, Patent No. 1,243,053; and application for patent filed January 10, 1917, Serial No. 141,558, Patent No. 1,246,067.

This invention relates to the manufacture 40 of rolled car wheels, disk-wheels or other circular bodies from properly heated ingots, blooms, blanks or other work-pieces, in an economical, commercial, expeditious and efficacious manner, whereby the whole car wheel, disk-wheel, or other circular body 45 may be completely rolled and otherwise operated upon in a simple and thoroughly practicable manner, various examples of which are for instance described in my said original application filed June 15, 1911, Serial No. 633,343, Patent No. 1,243,050, and in my application filed October 10, 1916,

Serial No. 124,921, Patent No. 1,243,051. This invention has particular reference to the method of and device or means for rolling or forming the entire opposite end faces of its hub.

In my said original application I have referred to several ways of forming the hub of a work-piece and have more particularly 55 shown and described the rolling or forming of the hub of the work-piece in a manner wherein flanges or shoulders of piercers or supporting centers may be made use of to form the end faces of the hub and, wherein 60 during the operating process of rolling or forming the hub, metal of the work-piece is forced radially to flow toward and around the piercers or supporting centers by means of the outer end operating parts of the 65 therein and herein-named edging and web-rolling rolls, and the lateral outward flow of metal caused by said edging and web-rolling rolls is forced partly against said 70 outer end operating parts of said edging and web-rolling rolls and partly against said 75 flanges or shoulders provided on said piercers or centers and thus the peripheral faces and part of the opposite end faces of the 80 hub of the work-piece are rolled or formed 85 by said edging and web-rolling rolls and the remaining parts of the opposite end faces of said hub formed by said edging and web-rolling rolls causing said lateral flow of metal to thus roll or form the whole 90 hub to desired form or shape. But, in this application, use is made of such piercers or work-supporting centers, shown and described in my said original application, 95 which have no such flanges or shoulders and the rolling or forming of the peripheral faces of the hub including the rolling or forming of the entire opposite end-faces of the hub of the work-piece is performed directly by said edging and web-rolling 100 rolls, this being, for instance, what I term in my said original application one of the many other shapes or forms the herein-named edging and web-rolling rolls may have; otherwise the rolling process or steps are similar to the ones particularly shown and described in my said original application.

The invention consists in the novel method

or process herein described and more particularly pointed out in the claims; and it also consists in the novel means, in the arrangement thereof, and in the arrangement 5 and combination of parts herein described and more particularly pointed out in the claims.

I prefer to carry out my invention with an apparatus or mill such as for instance 10 described and claimed in my aforesaid original application and in applications filed by me and having the hereinbefore-mentioned serial numbers and filing dates.

In the accompanying drawings, in which 15 I illustrate my invention together with devices or means I prefer to employ in carrying out my invention:

Figures 1, 2, 3 and 4 illustrate, according to my invention, certain piercing and rolling or forming steps for producing the dished car wheel, for instance shown in Figs. 4 20 or 12, all as hereinafter described and also partly described in my said original application.

25 Figs. 5, 6, 7 and 8, for instance, illustrate, on a smaller scale, rolling means and methods hereinafter described and which are the same as shown and described in my said original application except that the outer 30 end operating portions of the edging and web rolling rolls herein shown are made longer, and which may be employed in carrying out my invention.

Fig. 9 shows for instance the center or 35 hub portion only of the body of an ingot, bloom, or other work-piece having the form or shape for instance as shown, and in position to be centered or pierced or penetrated and centered according to my invention as 40 described in my said original application.

Fig. 10 shows the center or hub portion of a work-piece about to be centered or penetrated and centered as described in my said original application.

45 Fig. 11 shows, for instance, the center portion of a blank or work-piece provided with a conical hole as shown, the blank or work-piece being shown in position ready to be centered or pierced or penetrated and centered, according to my method described in my said original application.

In Figs. 12, 13 and 14 are shown for instance diametral sectional views of car wheels rolled or formed in accordance with 55 my invention, the same being shown with the hub bored. In Fig. 12 said car wheel is shown dished. In Fig. 13 said car wheel has its web formed in undished position, that is at right angles with the axis of the wheel, 60 but the hub of this wheel is not formed central to the web but is formed into the position required of a dished wheel, that is the hub is in the same position as is the hub in Fig. 12. In Fig. 14 said car wheel is 65 shown undished.

In Fig. 15 is shown in plan view, a portion of a finished car wheel rolled or formed in accordance with my invention.

It is to be understood that I do not intend to limit myself to the use of the particular parts herein shown, nor to the use of the apparatus or mill shown and disclosed in my said original application, as other means may hereafter be devised for carrying out my invention in a practicable manner.

Similar characters of reference indicate corresponding parts throughout the several views, and with reference to my said original application:

E, E are the spindles or axles named herein in the work-supporting axles which also serve other purposes and which are oppositely-arranged in alinement and spaced apart. Said spindles or axles E, E are 85 also interchangeable with axles differently shaped or formed. At one end of each of said axles, that is, at the adjacent ends of said axles are interchangeably or removably fastened thereto the herein named piercers 90 or work-supporting centers, or work-supporting means, for instance E¹, E¹, &c. These piercers, or work-supporting centers, or work-supporting means may also be differently formed to serve other purposes, 95 such for instance as forming dies, &c. There is practically no limit to the forms or shapes that said piercers, or supporting means may have or the purposes they may be used for. In the operating processes herein described, 100 piercers or centers E¹, E¹ formed as shown, and also as shown and described in my said original application, are used; that is, said piercers or centers are each provided adjacent its piercing or penetrating or centering 105 part e³³ with an extension e⁴² having a straight or approximately straight peripheral face, the diameters at the adjoining portions of said extension and said piercing or penetrating or centering part being the 110 same or substantially the same.

F, F¹ and F² represent the work-piece, from some of the various forms or shapes it may have when put into the apparatus or mill to some of the many various forms or 115 shapes the finished or partly finished article or product may have, as more fully described in my said original application.

Said piercing or work-supporting means are located one at each side of the work-piece, and preferably revolve with the work-piece. During the rolling or operating process, or during the piercing or penetrating or centering process said piercing or work-supporting means are moved longitudinally 125 toward each other or away from each other, or one with the other; or they may be otherwise moved as may be required or desired, and as more fully described in my said original application.

By the words "centering, or piercing, or penetrating and centering" used herein, I mean that, the ingot, bloom, blank or other work-piece is centered, or pierced, or penetrated and centered in the apparatus or mill, by forcing either one or both said piercers or work-supporting means into or against said work-piece by their pressure means operatively connected therewith, as and in the 10 manner fully shown and described in my said original application.

M, M are the herein named work-supporting heads which rotatably support said spindles or axles E, E. Said heads M, M are oppositely arranged in alinement and spaced apart and are longitudinally movable with their said axles E, E and piercers or centers, for instance E¹, E¹, in line with the axis of the work-piece, by their pressure means operatively connected therewith as for instance described in my said original application.

J, J, are the roll shafts, which are located and movable as herein shown and as more fully shown and described in my said original application and, each of said shafts J, J has at one of its ends one of the herein named edging and web rolling rolls. Said rolls are either attached to said shafts in such a way that the whole roll may be driven by the shaft, or only part of the roll may be driven by the shaft and the other part be permitted to turn loose; or the whole roll may be permitted to turn loose on the journal removably fastened to the shaft, as shown and described in my said original application.

J⁶⁹, J⁶⁹, &c., (J⁶⁹, J⁶⁹ being what I term in my said original application one of the many other shapes or forms that the herein named edging and web rolling rolls may have) are, 0 for instance, sets of the said edging and web rolling rolls. These rolls with their shafts J, J are laterally and also axially movable and are interchangeable with other shaped rolls. There is practically no limit to the forms or 5 shapes that these rolls may have and to the purposes for which they may be used. These rolls, as for instance J⁶⁹, J⁶⁹, are connected together by equalizing mechanism in such manner that said rolls may be connected with 10 or be disconnected from said equalizing mechanism without disconnecting said rolls from the coöperating pressure cylinders or pressure devices operatively connected with said rolls, as for instance described in my 15 said original application, or they may be otherwise arranged if desired.

K is the herein named tread or face rolling roll, or face beaking, or face roughing roll which acts against the peripheral face of the work-piece to roll said face to a beaked or rudimentary form, to partly finished form, or to finished form, as and for the purpose hereinafter described and as more fully shown and described in my said original application. This roll is movable toward

and against and also away from the peripheral face of the work-piece and it is also laterally movable, all as described in my said original application. The peripheral or rolling face of this roll and the whole roll may 70 have many different shapes or forms, as for instance shown and described in my said original application. There is practically no limit to the forms or shapes this tread or face rolling roll may have.

G, G are the roll shafts which are located and movable as herein shown and as more fully shown and described in my said original application and, which have at their outer or adjacent ends the herein named web 80 finishing rolls.

G¹, G², &c., (for other formed web finishing rolls see for instance my said original application) are, for instance, sets of said herein named web finishing rolls. These rolls 85 with their shafts G, G are laterally movable and are also axially adjustable or movable and are interchangeable with other shaped rolls. There is practically no limit to the forms or 90 shapes that these rolls may have and to purposes for which these herein named web finishing rolls may be used. These rolls, as for instance G¹, G², are connected together by equalizing mechanism, in such manner that they may be connected with or be disconnected from said equalizing mechanism, without disconnecting said rolls from the coöperating pressure cylinders or pressure devices operatively connected with said rolls, as for instance described in my said original 95 application; or they may be otherwise arranged if desired.

H is the herein named tread or face finishing roll which acts against the peripheral face of the work-piece. This roll is movable 105 toward and against and also away from the peripheral face of the work-piece. The peripheral or rolling face of this roll and the whole roll may have many different shapes or forms, as for instance shown and described in my said original application. There is practically no limit to the forms or 110 shapes this tread or face finishing roll may have.

Said face rolls H and K may also be 115 moved toward and against and also away from the peripheral face of the supported work-piece either together or independently of each other and for this purpose are connected together by equalizing mechanism in 120 such manner that said rolls may be connected with or be disconnected from said equalizing mechanism without disconnecting said rolls from the coöperating pressure cylinders or pressure devices operatively connected 125 with said rolls, as for instance shown and described in my said original application, or they may be otherwise arranged if desired.

In rolling car wheels or similar articles, 130

as for instance illustrated in the Figs. 1 to 8 inclusive, the lateral thickness or width of the face roll K is the same as is the lateral thickness or width which the outer or rim portion of the car wheel or similar article is to have when rolled to finish, as shown for instance in Figs. 1 to 8 inclusive. With said roll K so formed and with, for instance, the rolls J⁶⁹, J⁶⁹ in said figures formed as shown and, with the peripheral rolling or operating face of said face roll K formed as shown and as and for the purpose herein-after described and as more fully described in my said original application and, with the inner rolling or operating portion of the web reducing roll part j²⁸ of each of the edging and web rolling rolls J⁶⁹, J⁶⁹ formed sufficiently conical, as and for the purpose herein-after described and as more fully described in my said original application, and, with all said three rolls situated in a plane passing laterally through the car wheel at one side of its axis and with said rolls moved and operated during the rolling or operating process, as and for the purpose herein-after described and as more fully described in my said original application, the metal in the peripheral face and total rim portion of the work-piece or car wheel is worked continuously during the rolling process upon all its surfaces simultaneously, and with the roll part, for instance j⁴³, of each of said edging and web rolling rolls formed to roll the entire end faces of the hub, as will be hereinafter more fully described, a rolling mechanism is provided and a novel method or process is employed, which to my knowledge, together with the results obtained thereby, was never done or accomplished before in rolling car wheels.

In the rolling as for instance illustrated in Figs. 1, 2, 3 and 4, said web finishing rolls, for instance G¹, G², are both positively driven side rolls and are oppositely located, one at each side of the work-piece as shown, and their shafts G, G are inclined to the sides of the work-piece. These web finishing rolls, during the rolling process, may operate against the web and inner rim part of the work-piece or wheel or other article, either together or independently of each other, and they are moved either together or independently of each other toward or against or away from the work-piece or wheel or other article, as the case may require, by the pressure mechanism shown and described in my said original application, or by any other equivalent means. In the rolling for instance illustrated in said Figs. 1, 2, 3 and 4, said web finishing rolls are preferably formed for instance as G¹, G²; that is, the roll part g¹³⁷ of each of said rolls G¹, G² is the herein-named web finishing roll part, operating as shown in Fig. 4 on the web and inner rim part of the wheel or

other article; and, the roll part g¹³⁷ of each of said rolls G¹, G² in the process illustrated in said figures is not operating against the work-piece, but in most cases is permitted to come in contact with or to press against the opposite sides of the tread or face finishing roll H, as shown in Fig. 4, thereby forming a stop for said web finishing rolls at or near the work-piece in the direction toward or against the work-piece and also assisting in turning or driving said tread or face finishing roll H by frictional contact therewith.

In the rolling as for instance illustrated in Figs. 1, 2, 3 and 4, said edging and web rolling rolls, for instance J⁶⁹, J⁶⁹, are both positively driven rolls and are oppositely located, one at each side of the work-piece, as shown, and, when in normal position, their shafts J, J may either be parallel or inclined to the sides of the work-piece, and during the rolling process said rolls J⁶⁹, J⁶⁹ may operate alternately against the entire end and peripheral faces of the hub and adjacent web part, the web part, and the inner rim and adjacent web part, and also upon the edges of the rim of the work-piece or wheel or other article, either together or independently of each other, and they may be moved laterally toward and against the work-piece or away from it, or with the same, either together or independently of each other by the pressure means operatively connected therewith, as described in my said original application, or by any other suitable means. Said shafts J, J may also be moved longitudinally in either direction, between the center or hub part and the rim part or periphery of the work-piece or wheel, or other article, forward or backward, or forward and backward as often as desired, such as the case may require, by the pressure means and shifting devices described in my said original application, or by any other suitable means. Said edging and web rolling rolls are formed so that during the rolling or operating process they come in contact with or are against the opposite sides of the tread or face rolling roll K and thereby also form with said roll K a stop for their lateral movement against the work-piece and thereby also assist in turning or driving said face roll K by frictional contact therewith, or, said lateral movements of said edging and web rolling rolls may be limited by any other suitable means, such as for instance described in my said original application.

In the rolling as for instance illustrated in the Figs. 1 to 8 inclusive, said edging and web rolling rolls are preferably formed as J⁶⁹, J⁶⁹; that is, the peripheral or operating faces of the roll parts j⁴³, j⁴³ of said rolls J⁶⁹, J⁶⁹ are formed substantially straight as shown and, are the parts which

are rolling or operating, as shown, against the opposite end faces of the hub of the work-piece during the rolling or forming process of the hub and, the parts j^{28} , j^{28} of said rolls J^{69} , J^{69} are the web reducing roll parts which may however have any other desired forms or shapes than herein shown, operating as shown alternately against the hub and adjacent web part, web part, and 10 rim and adjacent web part of the work-piece, wheel or other article; that is, said web reducing roll parts j^{28} , j^{28} of said rolls J^{69} , J^{69} , with their outer rolling or operating portions, are operating upon the web and the 15 hub parts and form or shape the hub parts as shown and as hereinafter described with reference to Figs. 1 and 2, and, with their inner rolling or operating portions are operating on the web part and the inner peripheral face or faces of the rim of the work-piece and roll said faces or inner rim portion sufficiently inclined toward the periphery of the work-piece, as and for the purpose hereinafter described and more fully described in my said original application. 20 The parts j^{29} , j^{29} of said rolls J^{69} , J^{69} are the edging roll parts, rolling or operating as shown upon the edges or opposite sides of the marginal or rim portion of the work-piece, wheel or other article and, the peripheral or operating faces of these roll parts j^{29} , j^{29} are formed substantially straight as shown and also limit the lateral flow of the metal in the work-piece between the roll 25 parts j^{28} , j^{28} of said rolls J^{69} , J^{69} and the periphery of the work-piece. Said roll parts j^{29} , j^{29} , during the rolling process herein shown, come in contact with or against the opposite sides of the tread or face roll 30 K, as shown; or such rolls may not have such web reducing roll parts j^{28} , but be for instance wholly formed conical as, for instance described in my said original application. 35 As fully shown and described in my said original application, I form the inner rolling or operating portion of the web reducing part j^{28} of each of said edging and web rolling rolls sufficiently conical so that the face of said conically formed portion is 40 sufficiently inclined from its lateral apex toward the inner end of its roll; that is to say, so that when for instance, the web reducing parts j^{28} , j^{28} of said rolls J^{69} , J^{69} are against the finished web, the said face of said inner conically formed portion of each of said roll parts j^{28} , j^{28} is sufficiently 45 inclined from the side of the web outwardly in the direction away from the axis of the work-piece, as for instance in Figs. 2 and 3 and as more fully shown and described in my said original application. Said inner inclination of each of said web reducing parts j^{28} , j^{28} I therefore form sufficiently large enough so as to roll the inner peripheral faces of the rim portion sufficiently in 50 clined outwardly toward the peripheral face of the work-piece so that during the rolling or forming of the rim portion for instance to the rudimentary form shown in Fig. 3 and as more fully shown and described in my said original application, the metal is caused to flow in the proper directions to assure compression of the metal in said rim portion to uniform or to practically uniform density, as is distinctly shown and diagrammatically illustrated in my said original application, wherein is also diagrammatically illustrated and distinctly shown the result of the rolling or forming of the rim of a car wheel rolled or formed as and in 55 the manner herein described and, in my said original application is also distinctly shown what is meant by the herein used words "sufficiently conical" or "sufficiently inclined". The pressures from said sufficiently inclined inner faces of said roll parts j^{28} , j^{28} applied against the inner peripheral faces of the rim portion, as shown for instance in Figs. 2 and 3 and more fully shown and described in my said original 60 application, during the rolling or forming of said rim portion have rolled said inner peripheral faces of the so rudimentarily formed rim portion sufficiently inclined, as shown in Fig. 3 and as distinctly shown and described in my said original application, which has caused the metal during said rolling or forming of the rim portion to flow in the proper directions to be compressed to uniform or to practically uniform density, 65 while at the same time the pressures against the lateral or opposite sides of the rim from the edging roll parts j^{29} , j^{29} of said rolls J^{69} , J^{69} have caused the metal to flow into the inner region of the rim and have rolled 70 the rim to desired lateral thickness. At the same time the pressure against the peripheral face of the rim portion from the face beaking or face roughing roll K having its rolling face K' formed as shown, has caused 75 the metal to flow also into the inner region of the rim and has rolled said peripheral face to the beaked or rudimentary form as shown in Fig. 3, thereby having rolled said metal in the rim and adjacent web portion simultaneously on all its surfaces by rolls situated in a plane passing laterally through said rim and web portions and therewith having compressed said metal simultaneously on all its surfaces to uniform density, 80 or practically so, while at the same time said rim portion has been rolled to said rudimentary form shown for instance in Fig. 3 and as more fully shown and described in my said original application. The so rudimentarily formed rim is then rolled with rolls situated at another point of the rim portion to finished form whereby its metal is still further condensed as and in the manner hereinafter described with reference to Fig. 85

4 and more fully shown and described in my said original application or in any other suitable manner. During the finishing rolling process with the rolls G^1 , G^2 and H shown in Fig. 4 and operating against the rim portion at another point thereof, the web finishing rolls G^1 , G^2 with their finishing roll parts g^{136} , g^{136} roll said inclined inner peripheral faces of the rim of the work-piece F^1 in Fig. 3 to the finished form, shown in Fig. 4, while the peripheral face finishing roll H rolls said beaked or rudimentarily formed peripheral face of the work-piece F^1 in Fig. 3 to the finished form shown in Fig. 4 and while the edging roll parts j^{29} , j^{29} of said rolls J^{69} , J^{69} are still operating in contact with the opposite sides of the rim at another point thereof and are limiting the lateral flow of metal and maintaining the lateral thickness in the rim to which the same has been rolled during the rolling process described with reference to Fig. 3; the combined actions of said rolls J^{69} , J^{69} , G^1 , G^2 and H during said finishing rolling process roll or form the rim and adjacent web portion to the finished form shown in Fig. 4 and more fully shown and described in my said original application wherein it is also distinctly shown and diagrammatically illustrated that in this process of rolling, as for instance illustrated in the Figs. 1, 2, 3 and 4, the metal in the whole rim portion except the metal forming the tread, flange and root of the flange may be rolled or worked to uniform or practically uniform density and to a greater degree of density than the metal in the hub and web portions and, said metal forming the tread, flange and root of the flange where the strength and resistance to wear is mostly needed is rolled or worked to still greater or to its maximum degree of density. It is, of course, to be understood that in order to produce said results, the rim portion must be rolled first, for instance, to the rudimentary form shown in Fig. 3 as and in the manner above described before the same is rolled to the finished form shown in Fig. 4, and that the rolling of said inclined inner peripheral faces of the rim and the rolling of said beaked peripheral face to their finished forms during the finishing rolling process will not disturb the density of the metal to which it has been compressed during the process described with reference to Fig. 3, but will compress the metal in the tread, flange and root of the flange where the strength and resistance to wear is mostly needed to still greater density, all of which is more fully shown and described in my said original application.

The piercing, or penetrating and centering with the said piercers or work-supporting centers E^1 , E^1 herein shown, and also the dishing, undishing and redishing of the

work-piece, is done as and in the manner more fully shown and described in my said original application.

The rolling with said edging and web rolling rolls may, in the process illustrated for instance in Figs. 1 to 4, be commenced at or near the center portion of the ingot, bloom, blank or other work-piece, as hereinafter described with reference to Figs. 1 and 2 and more fully shown and described in my said other applications.

In the Figs. 1 and 2, I have for instance illustrated in brief, piercing or penetrating or centering process or steps and the method for rolling or forming the entire center or hub portion of a car wheel or other circular body including the rolling or forming of the entire opposite end faces of the hub with rolls such as I prefer to employ in carrying out the process illustrated in said Figs. 1 to 4 inclusive. In Fig. 1, the properly heated blank or work-piece F , shown in diametral section, may have a thickness which is either the same or greater than the length which the hub of the car wheel or other circular body is to have when rolled to finish, or it may have a thickness which is for instance the same, or greater, or less than the lateral thickness or width which the marginal or rim portion of the car wheel is to have when finished. The work-piece F shown in Fig. 1 has been brought into the position shown by a positioning or raising, lowering and retaining device, such for instance as shown and described in my said original application, and in which position the outer portion or periphery of the work-piece is coaxial or approximately so with the piercers or work-supporting centers E^1 , E^1 and in which position the work-piece F is then pierced or worked to uniform or practically uniform density and to a greater degree of density than the metal in the hub and web portions and, said metal forming the tread, flange and root of the flange where the strength and resistance to wear is mostly needed is rolled or worked to still greater or to its maximum degree of density. It is, of course, to be understood that in order to produce said results, the rim portion must be rolled first, for instance, to the rudimentary form shown in Fig. 3 as and in the manner above described before the same is rolled to the finished form shown in Fig. 4, and that the rolling of said inclined inner peripheral faces of the rim and the rolling of said beaked peripheral face to their finished forms during the finishing rolling process will not disturb the density of the metal to which it has been compressed during the process described with reference to Fig. 3, but will compress the metal in the tread, flange and root of the flange where the strength and resistance to wear is mostly needed to still greater density, all of which is more fully shown and described in my said original application.

The hub portion of the work-piece F is then rolled with the said piercers or centers E^1 , E^1 and their extent of piercing or penetrating into the opposite sides of the work-piece is limited or regulated as and in the manner for instance shown and described in my said original application and, operated on with the herein named edging and web rolling rolls for instance J^{69} , J^{69} which, while rotating the work-piece, are forced or rolled against and into the opposite sides of the work-piece and are rolling or forming the hub and, during this process of forming the hub, the ends of the parts j^{43} , j^{43} of said rolls J^{69} , J^{69} are either in contact with the peripheral faces of said piercers or centers E^1 , E^1 , as for instance shown in Figs. 1 and 2, or come against said peripheral faces of said piercers or centers E^1 , E^1 during the hub forming process as for instance herein described with reference to Figs. 1 and 2; thus the hub is rolled finished to the form shown for instance in Fig. 2 including the piercing or penetrating or centering of the work-piece and the hub rolled or formed smooth by rolling with said rolls J^{69} , J^{69} on all its

- surfaces and to desired form or shape without leaving a raised undesirable circular portion or fin which would have to be removed afterward by turning or other costly means.
- 5 In Fig. 2, the work-piece F shown in Fig. 1, is shown pierced by the piercing or penetrating parts e^{39} , e^{39} of said piercers or centers E^1 , E^1 and rolled with said rolls J^{69} , J^{69} and K to the form shown, while the 10 work-piece is supported by both said piercers or work-supporting centers E^1 , E^1 , as shown. Said piercing or penetrating or centering may be done either before or during said process of rolling the hub portion, and said 15 positioning or raising, lowering and retaining device described in my said original application is moved away from the work-piece either after or during the piercing or centering process.
- 20 In the Figs. 1 to 4 inclusive, I have for instance illustrated in brief, rolling or forming process or steps such as I prefer to employ for completely rolling or forming and dishing the car wheel shown at F^2 in Fig. 4, 25 including the rolling of the entire opposite end faces of the hub and also the piercing or penetrating and centering of the properly heated work-piece. In Fig. 1, the properly heated blank or work-piece F shown in diametral section may have, as before stated, a 30 thickness which is either the same or greater than the length which the hub of the car wheel is to have when rolled to finish, or it may have a thickness which is, for instance 35 the same, or greater, or less, than the lateral thickness or width which the marginal or rim portion of the car wheel is to have when rolled finished. Fig. 1 shows said work-piece F brought into the position shown by 40 said positioning, or raising, lowering and retaining device, and in this position the outer portion or periphery of the work-piece is coaxial, or approximately so, with the piercers or work-supporting centers E^1 , E^1 . 45 In this case said piercers or centers are formed as shown and the lengths of their penetrating portions e^{39} , e^{39} are made to suit the location of the web portion of the car wheel, as shown; that is, the web portion of 50 the wheel in this case will be formed in the center of the length of the hub of the wheel and said penetrating portions of said piercers or centers E^1 , E^1 will both have the same length, which may reach to or near 55 the center of the thickness of the finished web adjacent the hub portion of the wheel, as shown. In this position of the work-piece, said piercers or centers E^1 , E^1 , by their pressure means operatively connected there- 60 with as for instance shown and described in my said original application or by any other suitable means, are moved or forced against the opposite sides of the work-piece and, the piercing or penetrating and centering and the rolling or forming of the work-piece, in- 65 cluding the rolling or forming of its hub portion to the form shown in Fig. 2, will begin and be performed in the following manner:—During said piercing or centering process, said piercers or centers E^1 , E^1 are 70 moved axially from their positions against the work-piece shown in Fig. 1 into the positions thereof shown in Fig. 2, in which latter positions the axial movements of said piercers or centers E^1 , E^1 are automatically 75 stopped and are rotatably retained in said positions during the rolling or operating process illustrated in Figs. 2 and 3, and, during said piercing or centering process the piercing or penetrating or centering parts 80 e^{39} , e^{39} of said piercers or centers E^1 , E^1 have been forced into the opposite sides of the work-piece to the extent or depths shown in Fig. 2 while said depths have been limited or regulated as and in the manner for in- 85 stance shown and described in my said original application, and thus the work-piece is rotatably supported at its center or hub portion by both said piercers or centers E^1 , E^1 . While so rotatably supported the work-piece 90 may also be automatically and firmly clamped between said piercers or centers E^1 , E^1 , as and for the purpose described in my said original application. The work-piece is 95 so retained in said clamped condition during the entire rolling or operating and dishing processes until it is rolled and dished to finished form or is rolled to undished form and ready to be removed. The oppositely ar- 100 ranged edging and web rolling rolls J^{69} , J^{69} shown at one side of the axis of the supported work-piece, in this case are both simultane- 105ously moved equal distances laterally during the hub forming process; for instance from their positions in contact with the peripheral faces of the extensions e^{42} , e^{42} of 110 said piercers or centers E^1 , E^1 , as shown in Fig. 1, to the positions thereof shown in Fig. 2, if the thickness of the work-piece is for instance nearly the same or is greater 115 than the length which the hub of the car wheel is to have when rolled to finish; or in case that the thickness of the work-piece is for instance the same, or greater, or less, than the lateral thickness or width which the 120 marginal or rim portion of the work-piece is to have when finished, the rolling with said rolls J^{69} , J^{69} may be commenced at a position somewhat away from said piercers or centers E^1 , E^1 ; that is to say, the outer end faces of 125 the roll parts j^{43} , j^{43} of said rolls J^{69} , J^{69} are a suitable distance away from the peripheral faces of said piercers or centers E^1 , E^1 and from there said rolls J^{69} , J^{69} are forced laterally into the opposite sides of the supported work-piece and are shifted or moved longitudinally toward said piercers or centers to force metal of the work-piece toward and around said piercers to form the hub until the outer end faces of said roll parts j^{43} , j^{43} 130

of said rolls J^{69} , J^{69} are in contact with the peripheral faces of said piercers or centers E^1 , E^1 as shown in Fig. 2. During this hub rolling or forming process, the outer operating portions of the roll parts j^{28} , j^{28} and the roll parts j^{43} , j^{43} of said rolls J^{69} , J^{69} are also rolling and limiting the flow of metal in said hub portion, which metal during said hub forming process is forced radially toward and against and around said piercers or centers E^1 , E^1 and laterally outward and which flow of metal is limited by said roll parts j^{28} , j^{28} and j^{43} , j^{43} of said rolls J^{69} , J^{69} and thus form said hub portion, while the face beaking or face roughing roll K may begin to act against the peripheral face of the work-piece as shown in Fig. 2. By this rolling or forming process of said hub the work-piece is rolled or formed from the form shown in Fig. 1, to the form thereof shown in Fig. 2, and when the hub is thus formed or during said hub forming process, said rolls J^{69} , J^{69} are in contact with the peripheral faces of said piercers or centers E^1 , E^1 , and, the edging roll portions j^{29} , j^{29} of said rolls J^{69} , J^{69} are then in contact with or against the opposite sides of the face roll K, as shown, and are limiting the lateral flow of the metal in the portion of the work-piece between the roll parts j^{28} , j^{28} of said rolls J^{69} , J^{69} and the periphery of the work-piece during the further rolling or operating process against the work-piece and thus the work-piece F is rolled, including said piercing and rolling or forming of its hub portion, from the form shown in Fig. 1 to the form shown in Fig. 2. It is to be understood that said piercing or centering of the work-piece may be done either before or during the said hub rolling process, and that said positioning, or raising, lowering and retaining device, hereinbefore mentioned, may be moved away from the work-piece either after or during said piercing or centering process.

Fig. 2 shows said work-piece F pierced or centered and rotatably supported and so rolled to the form shown with its hub completely rolled or formed and with both said rolls J^{69} , J^{69} in contact with or against the peripheral faces of said piercers or centers E^1 , E^1 . With the rolls J^{69} , J^{69} thus positioned, the web portion of the work-piece may be reduced or rolled to its desired thickness in the following manner, forming part of said rolling or forming process or steps illustrated in Figs. 1 to 4 inclusive:—Said rolls J^{69} , J^{69} , during the rolling or forming process of the web, may be moved longitudinally or radially with respect to the work-piece from their positions adjacent the hub portion shown in solid lines in Fig. 2 and shown in dotted lines in Fig. 3, to the positions adjacent the rim portion shown in Fig. 3, and during said longitudinal or radial movements of said rolls J^{69} , J^{69} the web reducing roll portions j^{28} , j^{28} of said rolls J^{69} , J^{69} are also rolling or reducing the thickness of the web portion of the work-piece to its desired thickness and rolling the inner peripheral faces of the rim of the work-piece to the rudimentary form shown and as and for the purpose hereinbefore described and more fully shown and described in my said original application, and, while simultaneously with said longitudinal or radial movements of said rolls J^{69} , J^{69} said roll K is operating against the peripheral face of the work-piece and rolls the same to the beaked or rudimentary form as for instance shown in Fig. 3 and as and for the purpose hereinbefore described and more fully shown and described in my said original application; or said rolls J^{69} , J^{69} when rolling or reducing said web portion to its desired thickness, may be moved longitudinally or radially with respect to the work-piece forward and backward as often as desired while simultaneously with said longitudinal or radial movements of said rolls J^{69} , J^{69} , said face roll K is against or is operating against the peripheral face of the work-piece and rolls the same to said beaked or rudimentary form, as for instance shown in Fig. 3 and more fully shown and described in my said original application. While the roll parts j^{29} , j^{29} of said rolls J^{69} , J^{69} are still operating in contact with the lateral or opposite sides of the rim portion, said finishing rolls G¹, G² and H shown at the other side of the axis of the work-piece begin operating against the so rudimentarily formed rim portion and roll with said rolls G¹, G² the so rudimentarily rolled inner peripheral faces of the rim of the work-piece to the finished form and roll with said roll H the so beaked or rudimentarily formed peripheral face of the work-piece to the finished form shown in Fig. 4. During this action the edging roll parts j^{29} , j^{29} of said rolls J^{69} , J^{69} are maintaining the lateral thickness of the rim to which the same has been rolled during the process and simultaneously with the operations of said rolls G¹, G² and H against the work-piece, the dishing may be done to dish the work-piece or wheel while the same is rotating to the form F² shown in Fig. 4; which dishing is done for instance as follows:—With the work-piece supported on said piercers or centers E¹, E¹ and with its hub or center portion automatically and firmly clamped laterally or axially between said piercers or centers E¹, E¹ and before the dishing commences, one of said work-supporting heads M, M with its said axle E and piercer or center E¹ now under constant and continuous pressure from its pressure cylinder operatively connected there-

with, as for instance shown and described in my said original application, causes one piercer or center E^1 to press automatically and continuously toward and against the 5 hub or center portion at one side of said work-piece, and the other work-supporting head M with its said axle E and piercer or center E^1 now under constant and continuous pressure from its pressure cylinder operatively connected therewith, as for instance shown and described in my said original application, causes the other piercer or center E^1 to press automatically and continuously toward and against the hub or 10 center portion of said work-piece at the other side of said work-piece. With these parts thus arranged, the dishing may take place while the work-piece is rotating in the following manner:—While either, any, 15 or all the driven or all the rolls are in operation, the pressure in the pressure cylinder operatively connected with one of said supporting heads M , M , with its said axle E and piercer or center E^1 at one side of 20 the work-piece, is gradually somewhat relieved or reduced, retaining therein however, the constant pressure required in said pressure cylinder to retain the aforesaid automatically clamped condition of the hub 25 or center portion of said work-piece laterally or axially between said piercers or centers E^1 , E^1 , thereby causing the pressure or force from the other cylinder to overcome the resistance of the piston-rod of said 30 cylinder operatively connected with said one supporting head M with its axle E and piercer or center E^1 at the other side of the work-piece and gradually moving both 35 said heads M , M with their axles E , E and piercers or centers E^1 , E^1 and with the center or hub portion of the work-piece or car wheel, into the position shown in Fig. 4, in which position the wheel is dished as 40 shown. In this position, if necessary or desired, the rolls may still be in operation for finishing and truing up the wheel to the form or shape F^2 shown in Fig. 4 and also for giving the surfaces of the tread and flange portions of the wheel a harder 45 or more durable wearing surface. Instead of so reducing the constant pressure in one of said pressure cylinders, said dishing of the work-piece or wheel can also be done, while the work-piece is rotating, by increasing the constant pressure in one of said 50 pressure cylinders so as to overcome the constant pressure in the other pressure cylinder. During the dishing or rolling and dishing operation, the rim of the work-piece, wheel or other article is supported by the rolls, as for instance shown in Figs. 3 or 4, and in Figs. 6 and 8. After the wheel or other article is completely dished and finished, the rolls are pulled back sufficiently 55 to clear the finished wheel or other article

to be removed, &c., all as fully described in my said original application.

As stated in my said original application, the dishing, undishing or redishing operation while the work-piece is rotating may 70 also be effected by retaining said piercing or work-supporting means E^1 , E^1 in fixed rotatable positions while the work-piece is so rotatably supported at its center or hub portion and is so laterally or axially clamped 75 by and between said piercers or work-supporting means E^1 , E^1 , as and in the manner before described, and by moving for instance the rolls J^{69} , J^{69} and K in Fig. 5 in a lateral direction, or in a direction parallel to the 80 axis of the work-piece or approximately so and while the said rolls J^{69} , J^{69} and K , or at least the rolls J^{69} , J^{69} , are kept in contact with the marginal or rim portion of the work-piece. In thus applying my invention 85 for dishing, the marginal or rim portion of the work-piece is moved laterally with respect to its central portion, or, for producing the same effect, both said piercers or centers and said rolls may be moved in opposite 90 directions parallel to the axis of the so supported work-piece while said work-piece at its center or hub portion is so supported and so laterally clamped and while for instance said rolls J^{69} , J^{69} are so kept in contact with 95 the marginal or rim portion of the work-piece.

Undishing and redishing may be done in a similar manner as the dishing. In undishing, the dished object is placed on said work-supporting centers and while so supported, 100 as above described, can be moved axially into proper position to suit the rolls, and then undished while the object revolves.

In a dished wheel, the web, that is the part 105 of the wheel between the hub part and the rim part, is in an inclined position, as for instance in a wheel F^2 shown in Figs. 4 and 12, and, in an undished wheel the web is in a straight position, that is, at right angles 110 with the axis of the wheel, or approximately so, as for instance in the undished finished wheels F^2 shown in Figs. 13 and 14. The web is therefore longer in dished position than in undished or straight position, and, 115 the extra length or difference between the length of the web of a dished and undished wheel is made up during my said dishing process in the following manner:—With reference to Figs. 3 and 4 for instance; Fig. 120 3 illustrates an ingot, bloom, blank or other work-piece rolled with the rolls J^{69} , J^{69} and K to the undished form or shape F^1 , as shown, then with the rolls J^{69} , J^{69} still in operation, the said finishing rolls G^1 , G^2 125 and H commence operating against said work-piece F , and the dishing may be commenced at the same time and in the manner before described, and when completely rolled and dished, the rolls J^{69} , J^{69} and G^1 , G^2 and 130

H as shown in Fig. 4 may still operate against the work-piece or wheel to its finish and may also continue to operate against the dished work-piece or wheel after the same is 5 rolled and dished, whereby the wheel is made perfectly true, to balance, and to gage or gages and whereby is also given to the surface of the tread and flange portions of the wheel a harder and more durable wearing 10 surface. The said necessary lengthening of the web is performed during the dishing process by rolling out with said rolls for instance G¹, G², the metal f, f near the inner rim part, as indicated by the clearances be- 15 tween the inner rim part of the work-piece or wheel and the web reducing roll parts j²⁸, j²⁸ of said rolls J⁶⁹, J⁶⁹, which metal was left there by said web reducing roll parts j²⁸, j²⁸ of said rolls, for instance J⁶⁹, J⁶⁹ as 20 shown, and thereby adding during the rolling and dishing process by my method of dishing or rolling and dishing, sufficient metal to the web part and providing there- by the required metal for said extra length 25 to the web part.

A car wheel or similar article may also be rolled in dished or undished form as and in the manner shown for instance in the Figs. 5 to 8 inclusive, and more fully shown 30 and described in my said original applica- 95 tion; that is to say, for instance, instead of rolling and dishing a car wheel or similar article with use of all the rolls above de- 100 scribed, with reference to Figs. 1 to 4 in- 105 clusive, a car wheel or similar article may also be rolled and dished or be not dished with only the use of the herein named edging and web rolling rolls, for instance J⁶⁹, J⁶⁹, and a tread or face rolling roll such as K, as for in- 110 stance illustrated in Figs. 5 and 6 and, of which Fig. 5 shows for instance a disk-wheel or center such as for instance used in tired car wheels, rolled as above described or similar thereto, to the undished form F¹ with said 115 rolls J⁶⁹, J⁶⁹ and K as shown and, Fig. 6 shows said undished disk-wheel rolled and dished with the use of said same rolls J⁶⁹, J⁶⁹ and K to the form of the dished disk- 120 wheel F² shown in Fig. 6 as and in the man- 125 ner before described or similar thereto, but without said other rolls; or, a car wheel or similar body may be rolled and dished or be rolled and not dished with only the use of the herein named edging and web rolling rolls, for instance J⁶⁹, J⁶⁹ and tread or face 130 rolling roll K and the herein named tread or face finishing roll H, as for instance illus- 135 trated in Figs. 7 and 8, of which Fig. 7 shows for instance an undished car wheel 140 rolled or partly rolled to the form F¹ with said rolls J⁶⁹, J⁶⁹, K and with or without said roll H and, in Fig. 8 said undished car wheel is shown rolled and dished with the rolls J⁶⁹, J⁶⁹, K and H to the form of the

dished car wheel F² shown in Fig. 8. In said 65 rolling illustrated in Figs. 5 to 8 inclusive, the inner circumferential or inner peripheral faces of the rim may also be rolled or formed sufficiently inclined as and for the purpose before described, and the peripheral face of the rim portion rolled to any suitable form desired, or rolled directly to desired finished form.

There is practically no limit to the forms or shapes the work-piece to be operated upon 75 may have, as for instance may be observed partly from the Figs. 9, 10 and 11 and as for instance shown and described more fully in my said original application. Fig. 9 shows for instance the center portion only 80 of an ingot, bloom, blank or other work-piece F, and it also shows said piercers or centers, for instance E¹, E¹, in position to be forced into the opposite sides of the work-piece during the piercing or penetrating 85 process to the extent thereof shown by the dotted lines.

Fig. 10 shows the center portion only of a work-piece F formed with a central hole, such for instance as shown; and it also shows 90 said piercers or centers, for instance E¹, E¹, in position ready to be forced into the opposite sides of the work-piece.

In Fig. 11 is shown for instance the center portion only of a blank or work-piece 95 which has previously been provided with a conical hole, as shown, and which is penetrated or centered by the piercers or centers, for instance E¹, E¹, as indicated by the dotted lines.

Fig. 15 shows in plan view the so finished 100 rolled car wheel F², and Figs. 12, 13 and 14 are diametral sectional views of car wheels rolled or formed similar to the car wheel above described with reference to 105 Figs. 1 to 4, and each is shown with its hub bored and each section is taken on a dotted line as 12—12 of a plan view there- 110 of similar to F² in Fig. 15, looking in direction of the arrows. In Fig. 12 is shown a 115 rolled and dished car wheel completely rolled and dished in accordance with my method. In Fig. 13 is shown a rolled car wheel completely rolled or formed in accordance with my method and having its web 120 formed during the rolling process in undished position; that is at right angles with the axis of the wheel, the hub of this wheel is not, however, formed central to the web, but it is formed into the position required of a dished wheel; that is, the hub of the wheel shown in Fig. 13 is in the same position as is the hub of the dished wheel in Fig. 12. In Fig. 14 is shown a rolled undished car wheel completely rolled or 125 formed in accordance with my method, the web of this car wheel being rolled or formed, during the rolling process, at right angles

with the axis of the wheel and central with the rim and hub portions of the wheel, as shown.

The process of rolling as herein shown and described, is the same as described in my said original application filed June 15, 1911, Serial No. 633,343, Patent No. 1,243,050, and also in my said application for method patent filed October 10, 1916, Serial No. 124,921, Patent No. 1,243,051. In said original application, each end of the hub in each figure is shown with two flat portions, one being the flat end portion of the hub proper and the other the flat end portion of a flange or extension, which latter may, however, in some cases be omitted. It is clear therefore that when it is desired to roll the flat end of said flange or extension, the outer end of the roll part j^{28} of each of said edging and web rolling rolls are made longer, for instance by an extension forming the roll part j^{43} at the outer end of the roll part j^{28} of each of said edging and web rolling rolls, for instance J^{69} , J^{69} herein shown and which roll parts j^{43} , j^{43} are adapted to roll and act against the entire opposite end faces of the hub of the work-piece, as herein shown and described, and it is to be understood that this extension or roll part j^{43} may be formed on to the end portion of any of or all the edging and web rolling rolls shown and described in my said original application filed June 15, 1911, Serial No. 633,343, Patent No. 1,243,050 and in my said application filed October 10, 1916, Serial No. 124,921, Patent No. 1,243,051. It will therefore be apparent that when one or both ends of the hub are to be formed without said flange or extension, the outer end of the roll part j^{28} will be formed or shaped accordingly, all of which embodies the principle involved in my said original application.

Where in the specification and claims the words "ingot, bloom or blank" are used, it is intended to mean the work-piece to be operated upon, and the word "work-piece" is used herein in a broad sense and is intended to include an ingot, bloom, blank, car wheel or any other unfinished or completely finished circular, or approximately circular object adapted to be rolled, rerolled, reworked or reformed either to entirely change its shape, or only partly change its shape or outline, or to change its dimensions in whole or part, as desired. In other words "work-piece" means any circular, or approximately circular object to be operated upon.

Where in the specification and claims the words "sufficiently conical" or "sufficiently inclined" are used with reference to said inner rolling or operating portions of the web reducing roll parts j^{28} , j^{28} of said edging and web rolling rolls for instance J^{69} , J^{69} , or with reference to the inner peripheral

face or faces or to the inner portion of the 65 marginal or rim portion of a work-piece or wheel, or other object, it is intended to mean, the inclination of said inner rolling or operating portion of said web reducing roll parts j^{28} , j^{28} being or to be formed, &c., 70 so as to cause the metal, during the rolling or forming of said rim portion, to flow in the proper directions to assure compression of the metal in said rim portion to uniform or to practically uniform density, as distinctly illustrated and described in my said original application.

In this application I have illustrated and described the use of said roll parts j^{43} , j^{43} formed onto the outer rolling or operating 80 portions of the web reducing roll parts j^{28} , j^{28} of said edging and web rolling rolls, for instance J^{69} , J^{69} ; and have, for instance, illustrated by a few examples processes or steps, such as I prefer to employ for piercing or 85 penetrating or centering and completely rolling or forming the hub portion onto work-pieces with said edging and web rolling rolls, for instance, J^{69} , J^{69} , and for completely 90 rolling or forming and dishing according 95 to my invention, properly heated work-pieces into completely finished rolled car wheels or other similar bodies, in the same apparatus or mill. It may here be stated that each edging and web reducing roll, as for instance J^{69} , J^{69} , has two roll portions j^{43} and j^{28} , serving respectively as a hub-end rolling or forming portion and a rim-edging portion, and that said two portions are separated by an enlarged rolling portion j^{28} serving to roll both the peripheral faces of the hub and to reduce and roll the web and to roll or form the inner peripheral faces of the rim of the car wheel. While the means illustrated and described are designed to practically 100 carry out the various steps of my method, it is to be understood that I do not wish to limit myself to the use of such means, as modifications thereof may still be made and employed and my invention practised thereby without departing from my invention or sacrificing any of the advantages thereof.

The foregoing description and accompanying drawings further fully set forth 115 my invention herein claimed together with portions of an apparatus or mill, such as fully shown and described in my said original application, for carrying out my invention herein claimed, and also illustrate 120 modifications in the arrangement and construction of said portions of said apparatus or mill, which modifications may be employed for carrying out my said invention. It is to be understood, however, that many 125 modifications and changes in the steps, operation and in the construction and arrangement of parts may still be made without de-

parting from my invention, as defined in the claims.

Certain features of my invention herein described are not all claimed herein, but 5 such features not herein claimed are covered by claims within applications filed by me and having the hereinbefore said filing dates, serial numbers and patent numbers.

It will be obvious to those skilled in the 10 art that changes may be made without departing from my invention as defined in the claims.

I claim as my invention:—

1. The method of rolling or forming car 15 wheels from heated ingots, blooms, blanks or other work-pieces, which consists in subjecting the work-piece to the action of piercing or penetrating and rolling processes which pierce or penetrate the work-piece at 20 its opposite sides forming thereby a rudimentary bore, or a part or parts thereof, and completely roll and shape the work-piece, including the opposite end faces of its hub, to the form or shape of the car wheel.
2. The method of rolling or forming car 25 wheels or other circular bodies, in an apparatus or mill, from heated ingots, blooms, blanks or other work-pieces with one heat and before the finished wheel or other finished body is removed from said apparatus or mill, which consists in subjecting the work-piece to the action of piercing or penetrating and rolling processes which pierce or penetrate or enter the work-piece at its 30 opposite sides forming a rudimentary bore, or a part or parts thereof, and completely roll or form the work-piece to the desired form or shape of the car wheel or other body including the opposite end faces of 35 its hub.
3. The method of rolling or forming car 40 wheels or other similar circular bodies, in an apparatus or mill, from heated ingots, blooms, blanks or other work-pieces, which 45 consists in subjecting the work-piece to the action of piercing or penetrating and rolling and dishing processes which centrally pierce or penetrate the work-piece at its opposite sides to desired depth or depths and 50 completely roll or shape the work-piece including the end faces of its hub, and dish the same to the desired form or shape of the dished wheel or other dished body.
4. The method of rolling or forming car 55 wheels or other similar circular bodies from heated ingots, blooms, blanks or other work-pieces, while the work-piece is supported in an apparatus or mill, which consists in subjecting the supported work-piece to the action of rolling and dishing processes which 60 completely roll or shape the work-piece including the entire ends of its hub and then dish the same to the desired form or shape of the finished dished wheel or other dished 65 body.

5. The method of rolling heated work-pieces having each a central or hub portion and piercing or penetrating the same while rolls rotate the work-piece and act against its central or hub portion, which consists in 70 moving or forcing under pressure a pair of aligned rotatably mounted and suitably formed work-supporting devices against opposite sides of the work-piece and centrally supporting the same, in applying rolls against 75 the work-piece and therewith rotating the same and rolling or forming the outer peripheral face or faces and the entire end faces of said central or hub portion, and in piercing the work-piece with either or both 80 of said work-supporting devices while or before rolling or forming said central or hub portion.

6. The method of rolling or forming a hub on heated work-pieces, which consists in 85 means for centrally and rotatably supporting the work-piece, in applying rolling pressures against the metal at opposite sides of the work-piece, in forcing metal of the work-piece radially inwardly, against and 90 around said work-supporting means and laterally against said rolling pressures, and in confining the metal of the hub portion between the peripheral faces of said supporting means and said rolling pressures. 95

7. The method of rolling or forming heated ingots, blooms, car wheel blanks, or other work-pieces into car wheels or similar bodies, which consists in applying rolling pressures or rolling means against all external surfaces of the work-piece and therewith first 100 rolling or forming or shaping the hub including its end faces and adjacent web portion, and in then rolling and forming the remainder of the web portion and the rim portion of the work-piece to desired forms or shapes. 105

8. The method of rolling or forming heated work-pieces into car wheels or similar bodies while the work-piece is rotating, which consists in first rolling or forming the central or hub portion of the work-piece as desired including its opposite end faces, and in then rolling and forming the web and the marginal or rim portion of the work-piece 110 to the desired forms or shapes. 115

9. The method of rolling or forming car wheels from heated ingots, blooms, blanks or other work-pieces, which consists in centrally supporting a work-piece, in applying 120 a pair of side rolls to opposite sides of the work-piece to reduce the thickness of the same between its hub or central and marginal portions, and in rolling both end faces of said hub or central portion to determine 125 the length which the hub is to have when completed.

10. The method of rolling or forming car wheels from heated ingots, blooms, blanks or other work-pieces, which consists in cen- 130

trally piercing or penetrating a work-piece at one side thereof, in suitably supporting the work-piece at the other side thereof, in applying a laterally and longitudinally movable side roll to the first-mentioned side of the work-piece and rolling the same to reduce the thickness of the work-piece where desired and simultaneously therewith force metal of the work-piece inwardly toward the axis of the work-piece to form a hub, and in rolling the peripheral face and the end face of the hub thus formed by means of said side roll.

11. The method of rolling or forming car wheels from heated ingots, blooms, blanks or other work-pieces, which consists in centrally piercing or penetrating a work-piece at one side thereof, in suitably supporting the work-piece at the other side thereof, in applying a laterally and longitudinally movable side roll to the first-mentioned side of the work-piece and rolling the same to reduce the thickness thereof and simultaneously force metal of the work-piece inwardly toward the axis of the work-piece to form a hub and also limit the outward lateral flow of the metal forming said hub.

12. The method of rolling or forming car wheels from heated ingots, blooms, blanks or other work-pieces, which consists in applying a pair of aligned piercers or centers to opposite sides of the work-piece to cause the same to enter or penetrate the work-piece to desired depth or depths, in applying a pair of opposite side rolls having end extensions provided with straight peripheral faces to opposite sides of the work-piece and reducing the metal between the central and marginal portions thereof, and in rolling said side rolls with their end faces in contact with said piercers or centers directly adjoining the entering or penetrating parts thereof.

13. The method of rolling or forming car wheels having hubs from heated ingots, blooms, blanks or other work-pieces, which consists in centrally and rotatably supporting a work-piece and in applying rolls to the exposed portions of the work-piece to roll the same into a finished car wheel having all exterior surfaces completely rolled, including both the entire end faces of the hub thereof.

14. The method of rolling or forming car wheels from heated ingots, blooms, blanks or other work-pieces, which consists in centrally piercing or penetrating a work-piece otherwise exposed for rolling action, in applying rolls to the exposed portions thereof to form a hub, a web and a rim, and in completely rolling said hub including its entire end faces, said web and said rim to finished form.

15. The method of forming a hub on a car wheel or similar object rolled from a heated

ingot, bloom, blank or other work-piece, which consists in centrally and rotatably supporting the work-piece, in applying a pair of longitudinally movable side rolls to the opposite sides of the work-piece, in rotating said side rolls and simultaneously therewith moving the same lengthwise to force metal toward the axis of the work-piece to form the hub and with said side rolls roll the peripheral and end faces of the hub.

16. The method of forming a hub on a car wheel or similar object rolled from a heated ingot, bloom, blank or other work-piece, which consists in centrally entering or penetrating the work-piece at one side thereof, in suitably supporting the work-piece at the other side thereof, in applying a convexly shaped roll having an end extension provided with a straight peripheral portion to the first-mentioned side of the work-piece, in rolling said roll into said first-mentioned side of the work-piece and moving the same lengthwise to force metal toward the axis of the work-piece to form the hub and with said end extension limit the outward lateral flow of the metal at the hub and roll the end of the hub thus formed.

17. The method of rolling heated objects into circular form with a hub portion, which consists in applying centers or piercers axially, or substantially so, against the object, each center or piercer having adjacent its piercing or penetrating part an extension provided with a straight or approximately straight peripheral face whose diameter directly adjoining said piercing or penetrating part is the same or substantially the same as the diameter of the directly adjoining portion of said piercing or penetrating part, in applying rolling pressures or rolling means laterally against the opposite sides of the object, in applying pressures against the object in radial, or substantially radial lines complementary to said pressures exerted laterally to force metal at opposite sides of the object against and around the peripheral faces of the piercing or penetrating parts of said centers or piercers and against said rolling means.

18. The method of rolling heated objects into circular form with a hub portion, which consists in applying a center or piercer axially, or substantially so, against the object, in applying lateral pressure from a roll against one side of the object at a radial distance from said center or piercer, and in applying pressure against the object in radial, or substantially radial lines complementary to the pressure exerted laterally, to force metal at said side of the object against and around the peripheral face of said center or piercer and against said roll.

19. The method of rolling or forming the center portion, or hub and adjacent web portion of car wheels or other similar objects

having each a web portion formed integral with its said hub, during the rolling or forming of the car wheels or other objects from heated ingots, blooms, blanks or other work-pieces, which consists in subjecting the work-piece to the piercing or penetrating action of a pair of alined oppositely-arranged piercers or work-supporting centers having each adjacent its piercing or penetrating part an extension provided with a straight or approximately straight peripheral face whose diameter directly adjoining said piercing or penetrating part is the same or substantially the same as the diameter of the directly adjoining portion of said piercing or penetrating part and by means of which piercers or work-supporting centers the work-piece is centrally pierced or penetrated or centered at its opposite sides and supported, in subjecting the work-piece at its opposite sides, either after or during said piercing or penetrating process, to the action of oppositely-arranged rotating edging and web rolling rolls which with their web-rolling portions roll and reduce the thickness of the metal in the web portion of the work-piece adjacent its central or hub portion to desired thickness of the web and roll or form the outer peripheral faces of the hub and which with their straight peripheral faced extensions operate against the end faces of the hub while simultaneously with or during part of this process the outer end faces of said straight peripheral faced extensions of said edging and web rolling rolls are brought and retained during said hub forming process in contact with or against the peripheral faces of the extensions of said piercers or centers and thus form said hub and adjacent web portion.

20. The method of rolling or forming the center portion, or hub and adjacent web portion of car wheels or other similar objects having each a web portion formed integral with its said hub, during the rolling or forming of the car wheels or other objects from heated ingots, blooms, blanks or other work-pieces having each a thickness which is less than the length which the hub of the wheel or other object is to have when finished, which consists in subjecting the work-piece to the piercing or penetrating or centering action of a pair of alined oppositely-arranged piercers or work-supporting centers to centrally pierce or penetrate or center the work-piece at its opposite sides to desired depth or depths and support the same, said piercers or centers being each provided adjacent its piercing or penetrating part with an extension having a straight or approximately straight peripheral face and a diameter adjacent its said piercing or penetrating part which is the same or substantially the same as the adjacent diameter of its said 65 piercing or penetrating part, in subjecting

the work-piece at its opposite sides, either after or during said piercing or penetrating process, to the action of oppositely-arranged rotating edging and web rolling rolls having web rolling portions and straight peripheral faced roll parts adjacent said web rolling portions and which web rolling portions roll and reduce the thickness of the metal in the web portion of the work-piece adjacent its central or hub portion to desired thickness of the web and cause metal to flow from the rolled region adjacent the hub portion outward and between said piercers or centers and the web rolling portions of said edging and web rolling rolls to make up 80 the length of the hub, and in limiting the outward flow of metal with said straight peripheral faced roll parts and thus form said hub and adjacent web portion.

21. The method of rolling heated ingots, 85 blooms, blanks or other work-pieces into objects having each a hub portion, a rim portion and a web connecting said hub and rim portions, which consists in supporting the work-piece centrally on rotatable centers or supporting means and rolling the same in the following manner: first,—in applying against opposite sides of the work-piece at one side of its axis, or at one side of its center portion, a pair of laterally and 90 longitudinally movable and laterally oppositely-arranged edging and web rolls having each a web reducing roll part serving also as a hub rolling or hub forming part and an inner rim rolling part, and an edging roll part; in moving said rolls longitudinally, that is, radially or approximately radially with respect to the work-piece, alternately toward the hub portion and toward the peripheral or rim portion of the 100 work-piece or forward and backward as often as desired to reduce the thickness of the metal in the web portion of the work-piece and to cause metal to flow alternately toward the hub portion and toward the rim portion of the work-piece; in confining the metal in its lateral flow in the hub portion and in the rim portion of the work-piece with said edging and web rolling rolls; and in applying a peripheral face roll against the peripheral face of the work-piece between said edging and web rolls to coat with the latter and roll a rudimentary rim and adjacent web portion; and second,—in applying a pair of oppositely-arranged side 110 or finishing rolls to opposite sides of the work-piece at another side of its axis or of its center portion and moving the same toward and against said so rudimentarily formed rim portion; in applying a peripheral face shaping or face finishing roll between said side or finishing rolls against the peripheral face of the so rudimentarily formed rim to coat with said last-mentioned rolls and roll said so rudimentarily 115 120 125 130

formed rim and adjacent web portion to desired finished forms or shapes while said edging and web rolls with their edging roll parts limit the lateral flow of metal in the 5 rim or roll the rim to desired width or lateral thickness.

22. The method of rolling or forming car wheels or similar objects from heated ingots, blooms, blanks or other work-pieces having 10 each about the volume or weight of the finished rolled car wheel or other finished rolled object, which consists in centrally piercing or penetrating or centering and rotatably supporting the work-piece, in applying 15 oppositely-arranged laterally and longitudinally movable rolls laterally against opposite sides of the work-piece and moving said rolls in radial or in practically radial lines with respect to the work-piece, forward 20 or backward, or forward and backward as often as desired to cause metal to flow in the directions of said movements and roll or form the web and alternately the hub and rim, in simultaneously with or during 25 said action of said rolls causing a face roll positioned between said rolls to act against the peripheral face of the work-piece and roll the same to desired shape or form and also limit the radial flow of metal toward 30 the periphery of the work-piece, and in limiting the lateral flow of metal in said hub and rim with said first-mentioned rolls.

23. The method of rolling or forming car wheels or other circular objects from heated 35 ingots, blooms, blanks or other work-pieces having each about the volume or weight of the finished rolled car wheel or other finished rolled object is to be but being larger in diameter than the finished rolled car wheel 40 or other finished rolled object is to be, which consists in applying piercers or centers axially against opposite sides of the work-piece for centrally piercing or penetrating or centering and rotatably supporting the 45 work-piece, each piercer or center having adjacent its piercing or penetrating part an extension provided with a straight or approximately straight peripheral face whose diameter directly adjoining said piercing or 50 penetrating part is the same or substantially the same as the diameter of the directly adjoining portion of said piercing or penetrating part, in applying oppositely-arranged laterally and longitudinally movable 55 edging and web rolling rolls against opposite sides of the work-piece and moving said rolls longitudinally, that is, in radial lines with respect to the work-piece, or substantially so, forward or backward, or forward 60 and backward as often as desired to cause metal to flow in the directions of such movements to form the web and alternately the hub and the inner circumferential face or faces of the rim, in simultaneously with or 65 during the action of said edging and web

rolls causing a face roll positioned between said edging and web rolls to act against the peripheral face of the work-piece and together with said edging and web rolls roll or work the metal in the rim and adjacent 70 web portion of the work-piece simultaneously upon all its surfaces situated in planes passing laterally through the work-piece at one side of its axis or at one side of its hub or center portion and cause metal to be 75 forced alternately toward the inner region of the rim and toward the axis of the work-piece and against and around the peripheral faces of said piercers or centers and against said edging and web rolls simultaneously 80 with rolling the work-piece to desired diameter.

24. The method of rolling or forming car wheels or other circular bodies from heated ingots, blooms, blanks or other work-pieces 85 having each about the volume or weight of the finished rolled car wheel or other finished rolled object but being smaller in diameter than the finished rolled wheel or other finished rolled object is to be, which consists in applying piercers or centers axially 90 against opposite sides of the work-piece for centrally piercing or penetrating or centering and rotatably supporting the work-piece, each piercer or center having adjacent its 95 piercing or penetrating part an extension provided with a straight or approximately straight face and whose diameter at the portion directly adjoining said piercing or penetrating part is the same or substantially 100 the same as the diameter of the directly adjoining portion of said piercing or penetrating part, in applying oppositely-arranged laterally and longitudinally movable edging and web rolling rolls against opposite sides of the work-piece and forcing or 105 rolling said rolls laterally into the sides of the work-piece and also moving said rolls longitudinally or approximately so, that is, in radial lines with respect to the work-piece or substantially so, forward or backward, or forward and backward as often as 110 desired to cause metal to flow in the directions of said movements and form the web and alternately the hub and the inner circumferential face or faces of the rim and also roll the opposite sides or ends of the hub and the opposite sides of the marginal or rim portion, or limit the lateral flow of 115 metal in the hub and in the marginal or peripheral portion of the work-piece, thereby causing the desired amount of metal to flow toward the periphery of the work-piece to enlarge its diameter, and simultaneously 120 with or during the action of said edging and web rolling rolls causing a face rolling roll positioned between said edging and web rolling rolls to act against the peripheral face of the work-piece and together with said edging and web rolling rolls roll the 125 130

rim of the work-piece to desired form or shape and to desired diameter.

25. The method of piercing and rolling heated ingots, blooms, blanks or other work-pieces into the form of wheels or other circular objects having each a hub, a web and rim, which consists in centrally piercing or penetrating the work-piece, in applying laterally and longitudinally movable and oppositely-arranged rolls against opposite sides of the work-piece and moving said rolls longitudinally or approximately so forward and backward, that is, in radial lines with respect to the work-piece, or substantially so, to cause metal to flow in the directions of such movements to form the hub, the web and the inner circumferential face or faces of the rim, in limiting the lateral flow of the metal in the hub and rim portions by means of said rolls, in limiting the flow of the metal toward the periphery, and in rolling the peripheral face of the work-piece to desired form.

26. The method of rolling or shaping heated car wheel blanks or other work-pieces into car wheels or circular bodies having each a hub portion, a rim or flanged rim portion and a web connecting said hub and rim portion, which consists in rotatably supporting the work-piece, in applying a pair of laterally and longitudinally movable oppositely-arranged rotating side rolls against opposite sides of the work-piece and operating them to roll or form or shape the hub as desired including its outer or opposite end faces, the web to desired thickness, the inner circumferential face or faces of the rim to desired form or shape, and the lateral thickness of the rim to desired thickness, in simultaneously with or during the action of said side rolls causing a face beaking or face roughing roll positioned between said side rolls to act against the peripheral face of the work-piece and together with said side rolls so roll said inner circumferential face or faces and said lateral thickness of the rim of the work-piece and roll its peripheral face to completely beaked or rudimentary form, and in then applying a peripheral face finishing roll against said so completely beaked or rudimentarily formed peripheral face and rolling said face to the desired shape of a flanged tread or to any other desired suitable shape.

27. The method of rolling or forming car wheels or other circular objects having each a hub portion, a rim or flanged rim portion and a web connecting said hub and rim portions, from heated ingots, blooms, blanks or other work-pieces having each a thickness which is less than the length of the hub in the finished rolled wheel or other finished rolled object is to be, which consists in axially moving and forcing under power or pressure a pair of aligned and rotatably

mounted and axially independently movable piercers or work-supporting members against the work-piece at opposite sides thereof so as to support the work-piece during the hub rolling or hub forming process, in applying 70 against opposite sides of the work-piece at a proper radial distance or distances from the axis thereof laterally and lengthwise movable oppositely-arranged rotating side rolls provided with straight or approximately straight peripheral faced extensions and arranged with their axes inclined or parallel to the sides of the work-piece, said straight or approximately straight peripheral faced extensions being adapted to operate upon the opposite end faces of said hub, in forcing or rolling said side rolls laterally into the sides of the work-piece, and moving said rolls lengthwise or radially or substantially radially with respect to the 85 work-piece in a direction toward the axis of the work-piece while rotating the work-piece, in applying piercing or penetrating pressure at the same time to said piercing or work-supporting members so as to pierce 90 or penetrate or center the work-piece and firmly support the same during the further operating process, said rolling and piercing process causing metal from said rolled and pierced portions of the work-piece to flow 95 outward laterally between and around the peripheral faces of said work-supporting members and said side rolls and against the straight peripheral faced extensions of said side rolls and thus roll or form the hub to 100 desired form or shape and to desired length, in moving said side rolls radially with respect to the work-piece toward the peripheral portion of the work-piece, in simultaneously with or during said action of the 105 side rolls causing a tread or face shaping roll positioned between said side rolls to act against the peripheral face of the work-piece and together with the side rolls roll said rim portion of the work-piece to 110 desired form or shape.

28. The method of rolling or forming car wheels or other circular bodies from heated ingots, blooms, blanks or other work-pieces, which consists in subjecting the work-piece 115 to the action of oppositely-arranged piercers or work-supporting centers having each adjacent its piercing or penetrating part an extension provided with a straight or approximately straight peripheral face whose 120 diameter directly adjoining said piercing or penetrating part is the same or substantially the same as the diameter of the directly adjoining portion of said piercing or penetrating part and which piercers or centers 125 centrally pierce or penetrate the work-piece at its opposite sides to form the rudimentary bore, or a part or parts thereof of pre-determined depth or depths and also support the same, in applying oppositely-ar- 130

ranged laterally and longitudinally movable side rolls laterally to opposite sides of the work-piece to rotate and to reduce the metal in the work-piece at the points of contact 5 of said side rolls, in moving said side rolls lengthwise, or radially with respect to the work-piece, in either direction, or alternately in both directions to cause metal to flow toward the central portion of the work-piece 10 to form and roll the peripheral faces of the hub and then toward the peripheral portion of the work-piece to form and roll the inner peripheral faces of the rim portion, in limiting the lateral outward flow of metal in 15 the center or hub portion and in the marginal or rim portion of the work-piece with said side rolls, and in applying rolling pressure to the peripheral face of the work-piece to roll the same to desired form or shape. 20 29. The method of rolling heated ingots, blooms, blanks or other work-pieces into objects having each a hub portion, a rim portion and a web connecting said hub and rim portions, which consists in supporting the 25 work-piece centrally on rotatable centers or supporting means in a fixed central position, in applying laterally against opposite sides of the work-piece a pair of oppositely-arranged laterally and longitudinally movable 30 edging and web rolls having their axes parallel or inclined to the sides of the work-piece and being provided with web reducing roll parts adapted to operate against opposite sides of the web portion, the peripheral 35 and the end faces of the hub and the inner peripheral faces of the rim of the work-piece, and with edging roll parts, in moving said edging and web rolls longitudinally or approximately so, that is, radially 40 or approximately radially with respect to the work-piece, alternately toward the hub portion and toward the peripheral portion of the work-piece to cause the web reducing roll parts of said rolls to reduce the thickness 45 of the web portion of the work-piece to form the web and to cause metal to flow toward the axis of the work-piece to form the hub and roll the peripheral and the end faces of the hub and, toward the periphery 50 of the work-piece to form the rim portion, in limiting with the edging roll parts of said edging and web rolls the lateral flow of metal in the portion of the work-piece between the web reducing roll parts of said 55 edging and web rolls and the periphery of the work-piece and operating upon the opposite sides of said portion of the work-piece, in applying a peripheral face roll between said edging and web rolls to coact 60 with the latter to completely shape the rim and peripheral face of the work-piece to desired form. 65

30. The method of rolling car wheels or other circular bodies from heated ingots, 65 blooms, blanks or other work-pieces, which

consists in moving and forcing a pair of alined and rotatably mounted piercers or work-supporting members against or into the opposite sides of the work-piece to centrally pierce or penetrate or center the work-piece and also to support the same during the rolling or operating process, in applying a pair of oppositely-arranged laterally and longitudinally movable roughing rolls laterally against opposite sides of the work-piece and operate them so as to roll or form the web and hub portions including the end faces of the hub portion as desired and the inner circumferential face or faces of the rim portion to rudimentary forms or shapes, 70 in simultaneously with or during the action of said roughing rolls causing a face beaking or face roughing roll positioned between said roughing rolls to act against the peripheral face of the work-piece to roll said face 75 to completely beaked or rudimentary shape, and in then applying a pair of oppositely-arranged finishing rolls to opposite sides of the work-piece to roll the so rudimentarily shaped inner circumferential face or faces 80 of the rim to finished forms or shapes and a peripheral face finishing roll against the so beaked or rudimentarily formed peripheral face of the work-piece to roll the same 85 to the desired form or shape. 90

31. In an apparatus or mill for rolling car wheels or other circular bodies, means for centrally piercing or centering a work-piece comprising a pair of alined rotatable axles having piercers or work-supporting 100 centers at adjacent ends adapted to pierce or penetrate and support the work-piece while rolled or operated upon and also assist in forming the hub portion of said work-piece, said piercers or centers being suitably formed 105 and being each provided adjacent its piercing or penetrating part with an extension having a straight or approximately straight peripheral face, the piercing or penetrating part and the extension of each piercer or center being of the same or substantially the same diameter at their meeting line. 110

32. In an apparatus or mill for rolling car wheels or other circular bodies, means for piercing or penetrating and rotatably supporting a work-piece and assist in forming or rolling the hub portion of the work-piece comprising a pair of alined and rotatably supported piercers or work-supporting centers, said piercers or centers being each provided adjacent its piercing or penetrating part with an extension having a straight or approximately straight peripheral face, the meeting ends of the piercing or penetrating part and the extension of each piercer or 115 work-supporting center being of the same or substantially the same diameter. 120

33. In an apparatus or mill for rolling car wheels or other circular bodies, means for piercing or penetrating a work-piece 130

- comprising a pair of alined rotatable piercers or work-supporting centers, said piercers or work-supporting centers being suitably formed, one of said piercers or work-supporting centers being provided adjacent its piercing or penetrating part with an extension having a straight or approximately straight peripheral face and being adapted to assist in forming or rolling the hub portion of the work-piece, the directly adjoining portions of the piercing or penetrating part and the extension of each piercer or work-supporting center being of the same or substantially the same diameter.
34. In an apparatus or mill for rolling car wheels or other circular bodies, means for centrally supporting a work-piece during the process of rolling or forming a hub portion thereon; said means comprising a pair of alined piercers or work-supporting centers and each piercer or work-supporting center being provided adjacent its piercing or penetrating part with an extension having a straight or approximately straight peripheral face, the adjoining portions of the piercing or centering part and the extension of each piercer or work-supporting center being of the same or substantially the same diameter.
35. In an apparatus or mill for rolling car wheels or other circular bodies, means for centrally supporting a work-piece and means for limiting the lateral outward end flow of metal at the center or hub portion of the work-piece during the process of forming or shaping said hub portion, said means comprising a pair of alined piercers or work-supporting centers provided each adjacent its piercing or centering part with an extension having a straight or approximately straight peripheral face, the adjoining portions of the piercing or centering part and the extension of each piercer or work-supporting center being of the same or substantially the same diameter, and a pair of laterally and longitudinally movable oppositely-arranged rotating side rolls adapted to act against opposite sides of the work-piece, each of said side rolls having a portion thereof adapted for limiting the said lateral or outward end flow of metal at the opposite ends of the hub during the hub forming or hub rolling process.
36. In an apparatus or mill for rolling car wheels or other circular bodies, means for centrally piercing or penetrating and rotatably supporting a work-piece comprising a pair of alined rotatable axles having piercers or work-supporting centers at adjacent ends, the piercing or penetrating or supporting part of each of said piercers or centers being formed tapered and the part adjacent its said piercing or penetrating or supporting part having a straight or approximately

straight peripheral face, the adjoining portions of the piercing or penetrating or supporting part and the part adjacent thereto being of the same or substantially the same diameter.

37. In an apparatus or mill for rolling car wheels or other circular bodies, the combination of means for centrally piercing or penetrating and supporting a work-piece having piercers provided each with an extension having a straight or approximately straight peripheral face, a pair of oppositely-arranged edging and web reducing rolls adapted to work against opposite sides of the work-piece in a direction from its peripheral portion toward its axis to reduce the thickness of the same within a certain circular region between its peripheral portion and its center or hub portion and thereby cause the metal to flow toward the axis or hub portion of the work-piece and laterally against the said rolls.

38. In an apparatus or mill for rolling car wheels or other circular bodies, the combination of means for centrally piercing or penetrating and supporting a work-piece having a piercer or center at one side provided with an extension having a straight or approximately straight peripheral face, a roll at one side of the work-piece adapted to act laterally against the work-piece and move in radial or approximately radial lines with respect to the work-piece toward its center or hub portion to reduce the thickness of the work-piece within a certain circular region between its marginal or peripheral portion and its center or hub portion and thereby cause the metal to flow toward the axis or hub portion of the work-piece and laterally against said roll.

39. In an apparatus or mill for rolling car wheels or other circular bodies, rolling means for rolling or forming a hub on a work-piece and limiting the lateral outward flow of metal in the opposite ends of said hub during the rolling or forming of said hub, and a pair of axially movable devices at opposite sides of the work-piece for centrally supporting the work-piece during the process of rolling or forming said hub.

40. In an apparatus or mill for rolling car wheels or other circular bodies, means for rolling or forming a hub on opposite sides of a work-piece and limiting the lateral outward flow of metal in the opposite ends of said hub during the rolling or forming of said hub, and a pair of members adapted to centrally engage the work-piece at opposite sides thereof.

41. In an apparatus or mill for rolling car wheels or other circular bodies, rolling means for rolling or forming a hub on a work-piece and limiting the lateral outward flow of metal in the opposite ends of said

hub when rolling or forming said hub, and a pair of members adapted to centrally engage the work-piece at opposite sides thereof, each of said members having a straight peripheral faced portion to assist in forming the hub portion of the work-piece when rolling or forming said hub.

42. In an apparatus or mill for rolling car wheels or other circular bodies, rolling means for rolling or forming a hub on a supported work-piece and limiting the lateral outward flow of metal in the end of said hub at one side of the work-piece when rolling or forming said hub, and a pair of supporting members engaging opposite sides of the work-piece at its center or hub portion and supporting the same, one of said members having a straight peripheral faced portion to assist in forming the hub portion at 20 said one side of the work-piece when rolling or forming said hub.

43. An apparatus or mill for rolling car wheels or other circular bodies, comprising rolling means for rolling or forming a hub 25 on opposite sides of a centrally supported work-piece and limiting the lateral outward flow of metal in the opposite ends of said hub during the rolling or forming said hub, said rolling means being adapted to be moved or operated laterally and also longitudinally.

44. An apparatus or mill for rolling car wheels or other circular bodies, comprising a pair of members adapted to centrally engage the work-piece at opposite sides thereof, and support the same, rolling means adapted for rolling or forming a hub on one side of said so supported work-piece and for limiting the lateral outward flow of metal in the 40 rolled or formed end of said hub when rolling or forming said hub.

45. In an apparatus or mill for rolling car wheels or other circular bodies, rolling means for forming or rolling a hub on the opposite 45 sides of a supported work-piece, and a pair of supporting members adapted to centrally engage opposite sides or ends of the work-piece and support the same, each of said members having adjacent its supporting or 50 engaging portion a straight peripheral faced portion adapted to assist in forming said hub.

46. In an apparatus or mill for rolling car wheels or other circular bodies, a pair of oppositely arranged side rolls adapted to work against opposite sides of the work-piece and being axially movable to travel toward and away from the axis or center portion of the work-piece, said pair of side 55 rolls being also adapted to operate against the opposite ends of the center or hub portion when rolling or forming said hub portion.

47. In an apparatus or mill for rolling car

wheels or other circular bodies, means for 65 centrally and rotatably supporting a work-piece being otherwise entirely exposed, combined with mechanism for completely rolling the work-piece to finished form on all its exposed surfaces including both end faces of 70 its hub.

48. In an apparatus or mill for rolling car wheels or other circular bodies, means for centrally piercing or penetrating and rotatably supporting a work-piece, and means 75 for rolling opposite side faces of the work-piece at all points between the piercing or penetrating parts of said piercing or penetrating means and the peripheral edge of the work-piece.

49. In an apparatus or mill for rolling car wheels or other circular bodies, means for centrally piercing or penetrating and rotatably supporting a work-piece, means for rolling opposite side faces of the work-piece 85 to desired form at all points between the piercing or penetrating parts of said piercing or penetrating means and the peripheral edge of the work-piece, and means for rolling the peripheral face of the work-piece to 90 desired form.

50. In an apparatus or mill for rolling car wheels or other circular bodies, means for rolling a hub portion, a web portion and a rim portion on the work-piece, said means 95 comprising a single rolling element having a hub-end rolling part, a rim-edging part, and a web reducing or web rolling part intermediate said hub-end rolling part and rim-edging part, said web reducing or web 100 rolling part serving also to roll alternately the peripheral surfaces of said hub portion and the inner peripheral surface of said rim portion.

51. In rolling mechanism, a laterally and 105 also longitudinally movable rolling member adapted to be applied to the side of a work-piece to reduce and roll the work-piece for rolling or forming a web portion and a hub portion thereon and having an extension at 110 its outer end adapted to roll the end face of said hub portion.

52. In rolling mechanism, a laterally and 115 also longitudinally movable and positively driven edging and web rolling roll having two straight peripheral faced portions and an enlarged convex portion intermediate said straight peripheral faced portions and means for positively driving or rotating said roll.

53. In rolling mechanism, a laterally and 120 also longitudinally movable edging and web rolling roll for rolling the side of a car wheel to form a hub, a web and a rim thereon, said roll having two straight peripheral faced portions and an enlarged intermediate portion adapted to reduce the thickness of the work-piece to form said web and hub,

one of said straight peripheral faced portions serving to gage the length and roll one end of said hub and the other serving to gage the width and roll the edge of said 5 rim.

54. In rolling mechanism, a laterally and also longitudinally movable side rolling roll having a rolling part adapted to roll the side of a work-piece and being provided 10 with a reduced extension adapted to roll one end of the hub of the work-piece.

55. In rolling mechanism for providing a work-piece with a hub, a longitudinally movable side roll having a roll part adapted to engage and reduce the thickness of the work-piece and to form the hub and being provided 15 with an end extension of smaller diameter than said roll part adapted to roll one end of said hub.

56. In rolling mechanism for rolling a car wheel from a flat-faced work-piece, a longitudinally movable side roll having two spaced roll parts adapted to engage the side of the work-piece and roll the same 25 in a plane at right angles to the axis of the work-piece, said side roll having an intermediate enlarged roll part adapted to reduce the thickness of the metal and form the hub, the web and the rim of the car wheel, said 30 two spaced roll parts being adapted to roll the side edge of the rim and the end of said hub.

57. In an apparatus or mill for rolling car wheels or other circular bodies, means for 35 centrally and rotatably supporting a work-piece being otherwise entirely exposed, combined with a pair of side rolls adapted to be applied to opposite sides of the work-piece to reduce the thickness of the same and 40 form a web and hub thereon, said rolls having substantially cylindrical end extensions adapted to engage both ends of the hub thus formed and roll the same.

58. In an apparatus or mill for rolling 45 car wheels or other circular bodies, a pair of central engaging means adapted to centrally engage and rotatably support a work-piece, a pair of side rolls adapted to engage opposite sides of the work-piece to reduce 50 the thickness thereof and form a web and a hub thereon, said rolls having extensions of smaller diameter adapted to engage and roll both ends of said hub.

59. In rolling mechanism, a pair of central supporting members adapted to centrally and rotatably engage a work-piece, and side rolls adapted to be applied to opposite sides of the work-piece and having their ends in contact with said supporting members, said side rolls being adapted to reduce 60 the thickness of the work-piece and form a web and hub thereon and being also adapted to roll the peripheral faces and both ends of said hub.

60. In rolling mechanism, a pair of centers or piercers adapted to enter a work-piece centrally from opposite sides, and a pair of side rolls having web reducing roll parts adapted to reduce the thickness of the work-piece for forming the hub and the web, 70 said rolls having also end extensions of reduced diameter, the ends of said rolls engaging said centers or piercers and the peripheral faces thereof engaging and rolling the ends of said hub. 75

61. In rolling mechanism, a laterally and also longitudinally movable rolling member adapted to be applied to the side of a work-piece to roll the same to desired form, said member having two spaced straight peripheral faced portions and an intermediate enlarged portion. 80

62. In rolling mechanism, a laterally and also longitudinally movable and positively driven rolling member adapted to be applied to the side of a work-piece to roll the same to desired form, said member having an oppositely inclined roll part at the outer end of said roll part having a straight peripheral faced extension. 90

63. In rolling mechanism, a pair of laterally and also longitudinally movable rolling members adapted to be applied to opposite sides of a work-piece to roll the same to desired form, each member having an oppositely inclined roll part and at each of the outer and inner ends of said roll part having a straight peripheral faced roll part. 95

64. In rolling mechanism adapted for rolling work-pieces into car wheels or other similar objects, a pair of rotatable supporting members adapted to centrally support a work-piece, and a pair of side rolls adapted for lengthwise movement and to engage opposite sides of the work-piece, said side rolls having roll parts adapted to reduce the thickness of the work-piece and force the metal toward the axis of the work-piece when moved lengthwise to form said hub, said side rolls having also end extensions of smaller diameter than said roll parts adapted to engage said supporting members and to gage the length and roll the ends of the hub formed by said roll parts. 100 110

65. In rolling mechanism adapted for rolling work-pieces into car wheels or other similar objects, a pair of rotatable supporting members adapted to centrally support a work-piece, and rolling means engaging all exposed portions of the work-piece and completely rolling a hub including both entire end faces, a web and a rim on said work-piece. 115 120

66. In rolling mechanism, means for centrally and rotatably supporting a work-piece otherwise fully exposed for rolling action thereon, and means for completely rolling the exposed portions of the work-piece to 125

form the same into a car wheel having a completely rolled hub including both end faces, a web, and a rim portion.

67. In rolling mechanism for rolling work-pieces into car wheels or other similar objects, means for centrally and rotatably supporting a work-piece otherwise exposed for action thereon, combined with a pair of side rolls having roll parts provided with oppositely inclined peripheral faces and adapted to engage the sides of the work-piece, reduce the thickness of the same and force metal inwardly toward the axis of the work-piece to form a hub, said roll parts forming the peripheral faces of said hub and having roll extensions in contact with said supporting means and also in contact with both ends of the hub so formed to roll the same to finish, the whole serving to roll the hub complete without fins or other undesirable projecting parts.

68. In rolling mechanism, two pairs of operating members, one pair serving as supporting means to centrally engage a work-piece at opposite sides thereof and the other pair serving as rolling means positioned at opposite sides of the work-piece and adapted to reduce the thickness of the work-piece between its central and peripheral portions and being also movable toward the center of the work-piece to force metal around said supporting means to form the hub and to roll the peripheral and end surfaces of said hub.

69. In rolling mechanism, a pair of aligned piercing or penetrating members adapted to enter the metal of a work-piece from opposite sides, and a pair of oppositely-disposed longitudinally movable rolls adapted to engage opposite sides of the work-piece to reduce the thickness of the same between the central and rim portions thereof and to force metal inwardly around the piercing or penetrating members to form the hub, said rolls having straight peripheral faced extensions adapted to limit the lateral outward movement of the metal around said piercing or penetrating members and roll the hub to proper length.

70. In rolling mechanism, means for centrally and rotatably engaging a work-piece to support the same, and a pair of side rolls adapted to reduce the thickness of the work-piece between its central and marginal portions to form a web, said side rolls having end extensions adapted to roll both end faces of the hub of the work-piece and gage the length of the hub and being also adapted to have the ends of said extensions engage said central supporting means.

71. In rolling mechanism, a pair of aligned piercers or centers adapted to centrally enter or penetrate opposite sides of a work-piece and having piercing or penetrating parts at their extremities which determine the length which the hub is to be when finished, and a

pair of longitudinally movable side rolls adapted to operate against opposite sides of the work-piece to reduce the thickness of the work-piece between the central and marginal portions thereof, said rolls having end extensions, the end faces of which engage the portions of said piercers or centers adjacent their piercing or penetrating parts.

72. In rolling mechanism, a pair of aligned piercers or centers adapted to centrally enter or penetrate opposite sides of a work-piece, a pair of longitudinally movable side rolls adapted to operate against opposite sides of the work-piece to reduce the thickness of the same between the central and marginal portions thereof, said rolls having end extensions provided with straight peripheral faces and whose end faces correspond to the shape of the portions of said piercers adjoining their entering or penetrating parts.

73. In rolling mechanism, means for centrally and rotatably engaging a work-piece including a piercer or center adapted to centrally enter or penetrate the work-piece at one side thereof, and a longitudinally movable side roll engaging the said side of the work-piece and having its end-face in contact with the exposed portion of said piercer or center.

74. In rolling mechanism, means for centrally and rotatably engaging a work-piece including a piercer or center adapted to centrally enter or penetrate the work-piece at one side thereof, and a longitudinally movable side roll engaging the said side of the work-piece to reduce the thickness of the same between its central and marginal portions, said side roll having an end extension provided with a straight peripheral face and being adapted to roll against the unreduced metal in the central region of the work-piece around said piercer or center, said extension being adapted to operate against or in contact with the end of said metal around said piercer or center and to have its end in contact with said piercer or center during the rolling or forming of the said central region or of the hub portion of the work-piece.

75. In rolling mechanism, a pair of aligned rotatable piercers or centers having each a piercing or penetrating part and an extension adjoining said piercing or penetrating part, said piercing or penetrating part and extension being of the same or substantially the same diameter at their meeting line, and a pair of side rolls adapted to roll against the opposite sides of the work-piece to form the web and hub thereof and having their ends in contact with said piercers or centers at or substantially at the meeting line of said piercing or penetrating parts and said extensions.

76. An apparatus or mill for rolling car

wheels or other circular bodies comprising a pair of face rolls acting together or alternately against the peripheral face of a work-piece, one of said face-rolls having at its 5 marginal portion a lateral thickness or width which is the same as is the lateral thickness or width which the rim or marginal portion of the wheel or other body which is to be rolled from said work-piece 10 is to have, two pairs of side rolls, each pair having its rolls arranged at opposite sides of the work-piece, said two pairs of side rolls having their shafts inclined to the sides of the work-piece and being adapted to act 15 together or alternately against the work-piece, each pair of said side rolls having one of said face rolls positioned between the same, one pair of said side rolls being axially movable, that is radially or substantially so with respect to the work-piece, and having each an edging roll part and a web 20 reducing roll part of larger diameter than the edging roll part, said web reducing roll part being adapted to operate against opposite sides of the web portion to reduce or roll the same to desired thickness, and also against the peripheral and end faces of the hub and the inner peripheral faces of the rim and, said edging roll parts of said last- 25 mentioned pair of side rolls extending over the sides of the marginal or rim portion at opposite sides of the work-piece or car wheel or other body and also over and against part of the opposite sides of the first-mentioned face roll and said web reducing roll 30 parts of said last-mentioned pair of said side rolls being formed adjacent said edging roll parts and having their outer rolling or operating portions formed so as to roll or form the peripheral faces and the opposite end 35 faces of the hub of the work-piece and also having their inner rolling or operating portions formed sufficiently conical so that the face of each of said conically formed portions is sufficiently inclined from its lateral apex toward the inner end of its roll so as to be adapted to roll with said rolls the inner circumferential faces of the rim portion of the work-piece sufficiently inclined outwardly toward the peripheral face of the 40 work-piece so as to cause the metal to flow in the proper direction to assure compression of the metal in the rim portion to uniform or to practically uniform density, substantially as described, and means for positively driving at least one of the rolls in each pair of said side rolls.

77. An apparatus or mill for rolling car wheels or other circular bodies, comprising 60 means to rotatably support a work-piece, a pair of axially movable edging and web rolls at opposite sides of said work-piece positioned in a plane passing transversely through the work-piece at one side of a plane

passing centrally through the work-piece, 65 said rolls having edging roll portions and web rolling portions and being adapted to act with their edging roll portions against the portion of the work-piece between the web rolling portions of said rolls and the periphery of the work-piece and with their web rolling portions being adapted to roll or form the hub including the peripheral and opposite end faces thereof and to roll the web portion of the work-piece to desired thickness and also to roll the inner circumferential faces of the marginal or rim portion of the work-piece sufficiently inclined outwardly toward the peripheral face of the work-piece so as to cause the metal 70 to flow in the proper direction to assure compression of the metal in the marginal or rim portion of the work-piece to uniform or to practically uniform density substantially as described, means for positively driving one 75 of or both said edging and web rolls, a pair of shaping or finishing rolls at opposite sides of the work-piece positioned in a plane passing transversely through the work-piece at the other side of the plane passing centrally through the work-piece and adapted to roll said inner circumferential faces and the adjacent web portion of the work-piece to desired finished form substantially as 80 described, means for positively driving one 85 of or both said shaping or finishing rolls, and means for swinging or moving each or each pair of said rolls laterally into and out of operative position.

78. An apparatus or mill for rolling car 100 wheels or other circular bodies, comprising means to centrally support a work-piece, a laterally and axially movable edging and web roll at each side of said work-piece at one side of a plane passing diametrically through the work-piece, said rolls being oppositely arranged and having edging roll portions and web rolling portions and being adapted to act with their edging roll portions against the portion of the work-piece 105 between the web rolling portions of said rolls and the periphery of the work-piece and with their web rolling portions being adapted to roll or form the web portion of the work-piece to its desired thickness and roll or form the hub part of the work-piece including the peripheral and opposite end faces thereof as desired and also to roll the inner circumferential faces of the marginal or rim portion of the work-piece to sufficiently inclined form substantially as and for the purpose described, means for positively driving one of or both said edging and web rolls, a shaping or finishing roll 110 at each side of the work-piece at the other side of said plane and adapted to roll said inner circumferential faces and the adjacent web portion of the work-piece to desired 115 120 125

finished form, and means for positively driving one of or both said finishing rolls.

79. In an apparatus or mill for rolling car wheels or other circular bodies, means for 5 rotatably supporting a work-piece, and a roll having its axis parallel or inclined to the side of the work-piece and acting against the side of said work-piece, said roll being movable with respect to the work-piece in 10 the direction toward the center or hub portion of said work-piece to cause the metal to flow toward the center of the work-piece to form the hub and roll the peripheral and one of the opposite end faces of the 15 hub.

80. In an apparatus or mill for rolling car wheels or other circular bodies, means for rolling a work-piece, a roll having its axis parallel or inclined to the side of the 20 work-piece and being radially movable alternately in the direction toward the axis and toward the periphery of said work-piece, said roll being in contact with said work-piece to cause the metal to flow alternately toward the axis and toward the periphery of the work-piece when so moved and being formed at the lateral apex of its 25 peripheral face with a curved or convexial surface adjacent to a surface tangential to said curved or convexial surface and at an acute angle with the axis of said roll as and for the purpose described, said roll having also a straight peripheral faced extension at its outer end operating-portion adapted 30 to roll or form one of the opposite end faces of the hub of the work-piece.

81. In an apparatus or mill for rolling car wheels or other circular bodies, means for rolling a work-piece, a roll acting against 40 the side of said work-piece and thereto, radially movable in the direction toward the center of said work-piece and in contact with said work-piece to cause the metal to flow toward the center thereof, said roll 45 being formed at the lateral apex of its peripheral face with a curved or convexial surface adjacent to a surface tangential to said curved or convexial surface and at an acute angle with the axis of said roll as and for the purpose described and being also 50 formed adjacent its outer end operating-portion with a straight peripheral faced extension adapted to roll or form one of the opposite end faces of the hub of the work-piece.

82. In an apparatus or mill for rolling car wheels or other circular bodies, means for rolling a work-piece, an edging and web 55 rolling roll having its axis parallel or inclined to the side of the work-piece and acting against the side of said work-piece and thereto also radially movable alternately toward the center and the periphery of said

work-piece and in contact with said work-piece to alternately cause the metal thereof 65 to flow toward the center and the periphery of the work-piece, the web rolling portion of said roll being of larger diameter than the adjacent edging roll portion and the inner operating portion of said web rolling portion 70 being formed at the lateral apex of its peripheral face with a curved or convexial surface adjacent to a surface tangential to said convexial surface and at an acute angle with the axis of said roll as and for the purpose described, and the outer end operating portion of said web rolling portion of said 75 edging and web rolling roll being formed to suit the peripheral face and the end face of the hub of the work-piece.

83. In an apparatus or mill for rolling car wheels or other circular bodies, the combination of a pair of side rolls at opposite sides of the work-piece positioned in a plane passing laterally through the work-piece at one 80 side of a plane passing centrally through said work-piece and arranged with their axes parallel or inclined to the sides or ends of the work-piece and adapted to act against said work-piece from opposite sides, a tread 85 or peripheral face roll positioned between said pair of side rolls and adapted to act against the peripheral face of the work-piece, each of said side rolls having an edging roll part and a web rolling part of 90 larger diameter than said edging roll part, said edging roll part having its peripheral rolling or operating face formed substantially straight and the edging roll parts of said side rolls being adapted to act 95 against the portion of the work-piece between said web rolling parts of said side rolls and the periphery of the work-piece and also extend over part of the opposite side faces of said face roll to come or 100 roll in contact with said face roll, said web rolling parts of said side rolls being formed adjacent said edging roll parts and adapted to reduce or roll the web portion of the work-piece to desired thickness, the inner 105 rolling or operating portions of said web rolling parts of said side rolls being adapted to roll and form the inner circumferential or inner peripheral faces of the marginal or rim portion of the work-piece, said web rolling parts of said side rolls having their said inner rolling or operating portions formed sufficiently conical so that the face of each 110 of said conically formed portions is sufficiently inclined from its lateral apex toward the inner end of its roll so as to be adapted to roll with said side rolls the said inner circumferential faces of the marginal or rim portion of the work-piece sufficiently inclined outwardly toward the peripheral face 115 of the work-piece to cause the metal to flow 120

125

in the proper direction to assure compression of the metal in said rim portion to uniform or to practically uniform density, substantially as described, said web rolling 5 parts having their outer rolling or operating portions formed to suit the desired form or shape of the hub to roll or form the peripheral and the entire opposite end faces of

the hub of the work-piece to its desired form and length.

In testimony whereof, I have hereunto set my hand.

LOUIS F. DIETER.
